UNITED STATES PATENT OFFICE.

GEORGE E. MAYO, OF POTSDAM, NEW YORK.

PULP-FEED REGULATOR.

Application filed October 1, 1928. Serial No. 309,670.

The invention relates to the art of paper making, and more particularly to an improved device for controlling the rate of flow of semi-liquid pulp from a stuff box to a 5 Fourdrinier screen or refining engine.

In the making of paper from pulp it is necessary that the amount of solid material in the pulp from the stuff box or chest be delivered to the Fourdrinier screen at a definitely fixed rate in order that the finished sheet of paper be of uniform thickness. For the purpose of obtaining such a constant feed or flow from a stuff box to a Fourdrinier screen or refining engine, it has been suggested to provide means for automatically controlling the volume of the pulp delivered per unit of time, but this method has the disadvantage of merely controlling the volume of the pulp delivered per unit of time without providing any means for compensating for the variations in the pulp mixture itself. It is obvious that, when the rate of feed of the entire pulp mixture is maintained constant and the ratio of solid to water in the mixture varies, the amount of solid delivered to the screen per unit of time will also vary and will result in variations in the thickness of the finished paper.

In Letters Patent No. 1,248,972, of December 4, 1917, granted to I. J. Witham and myself, we described a device for controlling the feed from a stuff box to a Fourdrinier screen in such a way as to cause a substantially constant amount of solid material to be delivered per unit of time, the device being so arranged as to compensate for variations of the ratio of solid to water in the mixture. Briefly stated, the device described in the above mentioned patent consisted of a hollow conical air container suspended in a stuff box and immersed in the mixture contained therein with its base alone open to the mixture. The air container mentioned was connected with a source of compressed air supply which delivered air to the container at as nearly a constant rate as possible and at a pressure sufficient to prevent the mixture from ascending into the container, the air from within the container instead continuously escaping therefrom. Due to the fact that a pulp mixture of varying consistency or density offered greater or less resistance to the escape of air from the container, the pressure within the container was built up in varying degree in accordance with the ratio of pulp to water

in the mixture, which ratio determines the density of the pulp mixture. By connecting the container to an air-operated mechanism controlling the pulp feed gate controlling flow of pulp from the stuff box we utilized the varying pressure in the container to control the feed of pulp in such a way that, though a varying quantity of mixture was delivered per unit of time, the rate of flow of solid material to the Fourdrinier screen was maintained substantially constant.

While the above described device has worked admirably, it has been found difficult to furnish compressed air to the container at a perfectly constant rate, so that at times the rate of flow of pulp from the stuff box has been influenced not only by the ratio of pulp to water in the mixture but also by the somewhat varying rate at which compressed air has been supplied to the container.

The present invention has as its main object the provision of means by which the feeding of pulp from the stuff box is controlled only by the ratio of solid to water in the pulp mixture, whereby variations in the ratio cause a greater or less amount of pulp to flow from the stuff box so that the rate of flow of solid material from the stuff box is always constant.

Another object of this invention is to provide means of the character described which requires a minimum of attention and which is simple and economical to construct.

With these and other objects in view, the nature of which will more fully appear, the invention will be more clearly understood by a reading of the following detailed description, the appended claims, and the two views illustrated in the accompanying drawings, in which:

Figure 1 is a plan view of a stuff box embodying my invention, and

Figure 2 is a vertical sectional view taken on the line 2—2 of Figure 1.

Like numerals designate corresponding parts in the two views illustrated.

In the drawings there is shown a stuff box A filled with pulp B which is introduced into the stuff box through a pipe C from a pump or other source of supply (not shown). The stuff box is provided with an overflow partition 1 by means of which excess pulp is discharged into a pipe 2 through which the excess is led back to the source of supply, the level of the pulp in the stuff box being in this

way maintained constant, regardless of the amount of pulp being used. The stuff box is further provided with a discharge opening 1^a across which extends a strainer grid 1^b, the 5 rate of discharge or feed of pulp through the opening being controlled by a pulp feed gate 1^c journaled in bearings 1^d in the strainer grid 1^b.

Suspended within the stuff box by any suitable 10 means and extending into the pulp B is an air container 3. The said container is open to the pulp at a point below the level thereof, preferably at its lower end, but closed at its upper end by the plate 5. The 15 plate 5 may be provided with a flange 6 for attaching it to the container 3.

In the drawings I have shown the air container 3 as of cylindrical shape, though of course a container of any other shape such 20 as rectangular, or triangular shape in cross section, could also be used.

A casing 7 is rigidly mounted upon the stuff box by means of brackets 8, and in this casing is located a diaphragm 9 comprising top and 25 bottom plates 10 and 11 respectively and collapsible side walls 12, the bottom plate 11 being fixed to the bottom of the casing 7, while the top plate 10 and the side wall 12 are spaced from the adjacent walls of the casing and are 30 free to move relative to the casing and at the urge of air pressure within the diaphragm chamber formed between the plates 10 and 11 and walls 12. The diaphragm chamber is 35 designated 9 and communicates with the interior of the air container 3 by means of a pipe line 13 which enters the container at 14 and the diaphragm chamber at 15, a valve 16 being interposed in the pipe line for shutting off communication of the diaphragm 40 with the air container when desired. A gate operating arm 17 is fulcrumed to a bracket 18 on the casing 7, as at 19, and extends from the fulcrum 19 across and beyond the stuff box. A diaphragm arm 20 is pivoted at one end to 45 a pair of lugs 21 on the casing 7 and is provided at its other end with a boss 22 which extends through the top of the casing 7 and rests upon the top plate 10 of the diaphragm to move up and down therewith. Slidably 50 mounted on the gate operating arm is an abutment 23 which may be locked in any desired position of adjustment by means of a set screw 23^a. The arm 17 overlies the arm 20 so that this abutment rests upon the diaphragm 55 arm 20 and causes the gate operating arm 17 to be rocked about the fulcrum 19 when the diaphragm top plate 10 is moved up or down in a manner to be hereinafter described. Obviously, by changing the position of the abutment 23 relative to the pivot 21 and the fulcrum 19, the amount of movement imparted 60 to the gate operating arm 17 by a given movement of the diaphragm arm 20 may be varied.

At the outer end of the gate operating arm 65 17 a number of weights 24 is adjustably-

slidably carried and serves to urge the outer end of the said arm 17 downwardly. A link 25 provided with a link adjusting turnbuckle 25^a is pivoted at one of its ends to the gate operating arm 17 as at 26 and has its other 70 end connected to a lifting ring 27 on the gate 1^c for raising and lowering the said gate as the gate operating arm 17 is raised or lowered in a manner to be presently described.

In the drawings there is also shown a pressure gauge 28 of conventional type mounted on the top plate 5 of the air container 3, the said gauge communicating with the container and being actuated by the pressure therein.

The manner of operation of the device may be briefly described as follows: It is assumed that the valve 16 has been opened to allow the interior of the air container 3 to communicate with the diaphragm 7. Pulp is then introduced into the stuff box through the pipe C, and, rising in the stuff box, will entrap a quantity of air in the container. When the pulp on the outside of the container has reached the level shown in Figure 2 it will overflow the partition 1 and be maintained at this level as previously described. Due to the pressure exerted by the column of pulp in the stuff box, some of the pulp will rise within the air container 3 and compress the air entrapped therein, the rising of the pulp inside of the said container stopping at such a level that the pressure exerted by the entrapped and compressed air is just balanced by the otherwise unbalanced head of pulp indicated at h. Assuming that the pulp so initially introduced is of the proper working consistency, the abutment 23 and the weights 24 are then adjusted along the gate operating arm so as to cause the gate 1^c to be held in such an open position as will allow the 105 rate of flow of pulp from the stuff box, which will result in delivering the solid material at the desired rate. As long as the ratio of solid material to water in the pulp mixture remains constant, the pressure of the air entrapped in the container 3 will remain the same and the gate 1^c will remain stationary, thus permitting a constant feed of pulp, and, since the ratio of solid to water is constant, a constant feed of solid material will likewise 110 be assured.

If, however, the ratio of solid material to water in the pulp decreases, it will be necessary to open the gate farther to allow a greater feed of pulp in order to still feed solid material at the same rate. The gate will be automatically opened as follows: When the ratio of solid matter to water decreases, the density of the pulp mixture will increase due to the fact that water has a higher specific gravity than the solid material used. The increase in density of the pulp will result in a greater upward pressure being exerted by the pulp, due to the head of pulp indicated at h, and the level of the pulp 120 125 130

within the container will thereby be raised until the entrapped air has been compressed to such a degree as will balance the diminished head of pulp h . The increased pressure 5 of the air in the container acts through the pipe 13 and on the under side of the diaphragm plate 10, raising the plate, which, by means of the diaphragm arm 20 and the abutment 23, will in turn move the outer end of 10 the gate operating arm upward to lift the gate and allow a greater feed of pulp from the stuff box to compensate by an increased volume flow of pulp of greater density for a reduced volume flow of pulp of lesser density 15 and to thus assure a constant flow of solid per unit of flow time. In a similar manner, when the ratio of solid material to water has increased so that a lesser air pressure will act on the diaphragm, the gate will be lowered to 20 reduce the feed of pulp and to thereby maintain constant the rate of delivery of solid material.

By a proper adjustment of the abutment 23 and the weights 24 it will be possible to 25 definitely fix the rate at which solid material will be delivered from the stuff box.

The gauge 28, being actuated by air under pressure in the air container 3, can be calibrated to accurately indicate the ratio of solid 30 material to water in the pulp mixture, since the pressure in the container is entirely dependent upon this ratio.

It will be gathered from the foregoing that the container 3 is in the nature of an air trap 35 in which an unchanging body of air is trapped by the pulp in the stuff box and compressed in degree according to the consistency of the said pulp.

It is apparent that I have provided a device which may be used to control the feed 40 of pulp from a stuff box in such a way as will insure a constant feed of solid material regardless of variations in the consistency of the pulp. My device is extremely reliable 45 and accurate, since for its operation it depends only upon the consistency of the pulp and not upon any outside influences which might be subject to continued variations tending to reduce the efficiency of the device. 50

It is obvious that my pulp feed regulator may be used in connection with the feeding of other mixtures of solid matter and liquid, and it is of course to be understood that 55 the details of structure and arrangements of parts may be variously changed without departing from the spirit and scope of my invention as defined in the appended claims.

I claim:

60 1. In a pulp feed regulator, the combination with a stuff box having a pulp discharge opening, of a pulp feed gate, and means for operating the gate to regulate the amount of pulp solid flowing through the feed gate per given time unit, said operating means in-

cluding an air container confining an unchanging body of air therein and open to the pulp at a point below its level in the stuff box, and pressure responsive means communicating with the container and actuated by the pressure of the air confined therein for positioning the gate and regulating the flow of pulp from the discharge opening. 70

2. In a pulp feed regulator, the combination with a stuff box having a pulp discharge opening, of a pulp feed gate, and means for operating the gate to regulate the amount of pulp solid flowing through the feed gate per given time unit, said operating means 80 including a fluid container confining an unchanging body of fluid therein and open to the pulp at a point below its level in the stuff box, and pressure responsive means communicating with the container and actuated by the pressure of the fluid confined therein for positioning the gate and regulating the flow of pulp from the discharge opening. 85

3. In a pulp feed regulator, the combination with a stuff box having means for maintaining a constant level of pulp therein, and a pulp discharge opening, of a pulp feed gate, and means for operating the gate to regulate the amount of pulp solid flowing through the feed gate per given time unit, 90 said operating means including an air container confining an unchanging body of air therein and open to the pulp at a point below its level in the stuff box, and pressure responsive means communicating with the container and actuated by the pressure of the air confined therein for positioning the gate and regulating the flow of pulp from the discharge opening. 95

4. In a pulp feed regulator, the combination with a stuff box having a pulp discharge opening of a pulp feed gate and means for operating the gate including an air container within the stuff box and open to the pulp at a point below the level thereof for confining an unchanging body of air within the container, pressure responsive means communicating with the container and actuated by the pressure of the air therein, and adjustable means connected to said pressure responsive means and to the gate for operating the gate when the pressure responsive means is actuated. 105

5. In a pulp feed regulator, the combination with a stuff box having a pulp discharge opening of a pulp feed gate and means for operating the gate including an air container within the stuff box and open to the pulp at a point below the level thereof for confining an unchanging body of air within the container, pressure responsive means communicating with the container and actuated by the pressure of the air therein, a gate operating arm, and means adjustably positioned on the arm and actuated by the pres- 115

sure responsive means for operating the arm and the gate.

6. In a pulp feed regulator, the combination with a stuff box having a pulp discharge opening of a pulp feed gate and means for operating the gate including an air container within the stuff box and open to the pulp at a point below the level thereof for confining an unchanging body of air within the container, pressure responsive means communicating with the container and actuated by the pressure of the air therein, a gate operating arm, means adjustably positioned on the arm and actuated by the pressure responsive means for operating the arm and the gate, and weights adjustably positioned on the arm and serving to urge it downwardly.

7. In a pulp feed regulator, the combination with a stuff box having a pulp discharge opening of a pulp feed gate and means for operating the gate including an air container within the stuff box and open to the pulp at a point below the level thereof for confining an unchanging body of air within the container, a pressure responsive diaphragm communicating with the container and actuated by the pressure of the air therein, a pivoted diaphragm arm adapted to be actuated by contact with the diaphragm, a pivoted gate operating arm overlying the diaphragm arm, an abutment adjustably positioned on the gate operating arm for contact with the diaphragm arm, and means connecting the gate operating arm to the gate at a point remote from the pivot on said arm.

8. In a pulp feed regulator, the combination with a stuff box having a pulp discharge opening of a pulp feed gate and means for operating the gate including an air container within the stuff box and open to the pulp at a point below the level thereof for confining an unchanging body of air within the container, a pressure responsive diaphragm communicating with the container and actuated by the pressure of the air therein, a pivoted diaphragm arm adapted to be actuated by contact with the diaphragm, a pivoted gate operating arm overlying the diaphragm arm, an abutment adjustably positioned on the gate operating arm for contact with the diaphragm arm, means connecting the gate operating arm to the gate at a point remote from the pivot on said arm, and adjustable means for urging the gate operating arm downwardly.

9. In a pulp feed regulator, the combination with a stuff box having means for maintaining a constant level of pulp therein of

an air container within the stuff box and open to the pulp at a point below the level thereof for confining an unchanging body of air within the container, and a pressure indicating gauge communicating with the interior of said container and responsive to the pressure therein.

10. In a pulp feed regulator wherein is provided a stuff box having a discharge opening and a gate to control the opening; means to trap an unchanging body of fluid in a manner for having its pressure varied in accordance with variations in density of pulp in the stuff box, and means actuated by the pressure of the said body of fluid to control the position of the said gate.

11. In a pulp feed regulator, a stuff box having means to maintain a constant level of pulp therein and a pulp discharge opening, a gate to control the discharge opening, a pressure actuated diaphragm, a fluid trap open at one point to communication with the pulp in the stuff box beneath the level thereof and at another point with the diaphragm and closed throughout otherwise to trap therein an unchanging body of fluid in a manner for causing the pressure of the trapped fluid to vary in accordance with variations in the density of the pulp in the stuff box, and means connected to the control gate and actuated by the diaphragm to position the gate according to the degree of density of the pulp in the stuff box.

12. In a pulp feed regulator wherein is provided a stuff box having a discharge opening and a gate to control the opening; means to trap an unchanging body of fluid in a manner for having its pressure varied in accordance with variations in density of pulp in the stuff box, and means actuated by the pressure of the said body of fluid to control the position of the said gate, said last named means comprising a pressure responsive diaphragm communicating with the trapped body of fluid and actuated by the pressure of the said body of fluid, a pivoted diaphragm arm adapted to be actuated by contact with the diaphragm, a pivoted gate operating arm overlying the diaphragm arm, means to connect the gate and gate operating arm for movement together, and an adjustable abutment member for causing the diaphragm arm and gate operating arm to interengage for the purpose described.

In testimony whereof, I have hereunto subscribed my name.

GEORGE E. MAYO.
